APPARATUS FOR BENDING A FLEXIBLE METAL WIRE OR STRIP

Willi Hasenfratz, Benken, Switzerland, assignor to Forschungs Anstalt fur Mechanik, Vaduz, Liechtenstein, an establishment of Liechtenstein

Filed Apr. 29, 1960, Ser. No. 25,632

Claims priority, application Germany Dec. 21, 1959

6 Claims. (Cl. 100—26)

This invention relates to an apparatus for bending flexible metal rods in the form of wire or strip.

It is known to bend a flexible metal rod in the form of wire or strip by inserting the rod axially into a guide channel with a contour corresponding to the desired form of bending. For removing the bent wire, there is provided a lateral gap which opens into the guide channel throughout the length thereof. In some constructions, this gap or slot is also open during the bending operation; consequently, the guide means for the rod are not closed on all sides, so that in some circumstances the rod can extend through the gap while it is being guided through the guide channel so that the desired bending is not effected. However, even when the bending operation takes place satisfactorily, it is possible for the bent rod subsequently to issue prematurely through the gap or slot.

It is true that there are also known constructions in which the guide channel is closed laterally during the bending operation and is only opened for extracting the bent or curved rod. However, this is effected by hinging the guide housing or by removing one side of the guide channel which is formed by parts of the housing wall. Both these arrangements can be used only with rectilinearly extending guide channels. Consequently, the guide channel is subdivided into a series of adjoining rectilinear partial channels which are disposed at a predetermined angle to one another and each partial guide channel must be separately opened and closed laterally. Apart from the complicated nature of this construction and the inconvenient manipulation required, the friction when pushing the rod through axially is impermissibly high.

An object of the present invention is to obviate these disadvantages of the known constructions. Accordingly, the invention provides a method of and apparatus for bending a flexible metal rod in wire or strip form by axial insertion into a guide channel having a path corresponding to the desired form of bending, from which channel it is removed in the bent or curved state through a lateral gap or slot opening into the guide channel throughout its length. The method of invention is characterised by the fact that at least three juxtaposed flexible tubes are so arranged to conform to the desired bending path that they enclose between them a longitudinally extending cavity and also have, at the most, a mutual spacing from one another which is less than the thickness of the rod to be bent, the rod being pushed axially through the cavity between the tubes and forming the guide channel and at least one tube being thereafter displaced laterally relatively to the other tubes to such an extent that a gap exceeding the thickness of the rod is formed between two tubes, the bent rod being removed laterally through this gap. The apparatus of the invention comprises at least three juxtaposed flexible tubes which between them define the cavity and guide components for holding these tubes in an arrangement corresponding to the predetermined bending path, at least one guiding component being so adjustable that, in one position, all tubes are positively held at a mutual spacing less than the thickness of the rod to be bent and the central cavity enclosed by the tubes forms a guide channel for the rod, whereas in another position of the said guiding component, a gap of an internal width ex-

ceeding the thickness of the rod and extending throughout the length of the channel is formed between at least two tubes. The flexible tubes have the advantage that they are adapted in the continuous path to any desired form of bending, and in addition offer a minimum resistance to the flexible rod being pushed through the cavity between the tubes, because the rod does not bear on guiding surfaces over its entire length, but only at individual punctiform positions or short lines. The invention is especially suitable for forming loops or the like for banding packages, the flexible rod consisting of metal bands or of metal wires of circular, elliptical, oval or other cross-section, such as are usual in this field. Flexible rods of this type are more especially used on wire-banding or strip-banding machines, in which the loop or the like is generally formed by direct mechanical looping around the package. However, the nature of the packages is not always suitable in order to serve at the same time as a bend former for the looping of the wire. Moreover, it is necessary for the package, on forming the loop, to be already in the position inside the machine which is necessary for the banding operation, whereas with the arrangement according to the present invention, the loop or the like can be produced independently of the package and the extraction of the loop from the guide channel, which takes only a short time, can be effected immediately as soon as the package has assumed the desired position so that it is possible to produce a more rapid completion of the entire banding operation and thus a more rapid flow of the successive packages.

In the accompanying drawings:

FIG. 1 is a perspective view of an apparatus according to the invention, in an open position,

FIG. 2 is an end view of the left-hand end of a housing of the apparatus in the closed position,

FIG. 3 is a view similar to FIG. 1, but showing a second embodiment,

FIG. 4 is a cross-section to a larger scale,

FIG. 5 shows diagrammatically an example of use, and

FIG. 6 is a plan view of a modification.

The construction illustrated in FIGS. 1 and 2, comprises a housing 1 which is of arcuate form and has a continuous recess 2 the cross-section is shaped as a T lying on its side. Arranged one above the other in the portion 3 of the recess 2 are two flexible tubes 4 and 5, while a third flexible tube 7 is arranged in the stem 6 of the recess. The housing is subdivided symmetrically of the stem 6 into two halves 8 and 9. The lower half 9 is split longitudinally into separate segments 10, 11 and 12, which are independently adjustable with respect to the half 8 transversely of the stem 6. In the closed position (shown in FIG. 2) the half 9 is moved up to the half 8 by exerting vertical forces P on the segments 10, 11 and 12 so that the three tubes 4, 5, 7 are positively held mutually abutting one against the other. In this position, a flexible rod 13 which is to be bent and has the form of a round wire can be pushed axially through a cavity 14 disposed between the tubes and serving as a guide channel. The tubes 4, 5, 7 preferably consist of helical springs of identical dimensions and having turns which bear positively one against the other, these turns being adapted continuously to the form or shape given by the recess in the housing 1. Nevertheless, the turns of the springs do not offer any considerable resistance to the movement of metal rod 13 between them since the rod 13 has only punctiform bearing on the individual turns of the springs which are circular in cross-section; in addition, the turns of the springs automatically centre the rod 13 because of their cross-section so that the rod cannot deflect from the central direction and cannot

strike against surfaces extending transversely of the direction of displacement.

After the wire has been pushed completely through the cavity or guide channel 14, it is freed therefrom by opening the housing, the half 9 being lowered into the open position shown in FIG. 1 by devices (not shown) and by converting the compressive forces P into oppositely directed tensile forces. The result of this movement is that a clearance exceeding the thickness of the rod 13 is formed between the two tubes 4, 5 located in the portion 3 of the recess 2. Consequently, the rod 13 can be removed between the tubes 4, 5 and the slot 16 which exists on the inside between the halves 8, 9 by pulling the rod at its two ends. The slot 15 on the outside has no influence on the extraction of the wire, since it is closed in the inward direction by the tube 7. As can be seen from FIG. 2, the slot 15 exists even when the housing is closed. The internal width of the slot 16 is somewhat greater than that of the slot 15. However, there is no objection to the slots 15 and 16 or only one of the slots being closed when the housing is closed. Nevertheless, it is advisable if there is some clearance between the housing halves 1, 9 when the housing is closed, as this ensures that the tubes 4, 5, 7 rest reliably one against the other and therefore that the guide channel 14 is closed around its length so that unintended egress of the rod 13 is prevented.

The construction illustrated in FIGS. 3 and 4 merely differs from the preceding construction by the fact that the recess 2 is shaped as an inverted T so that its stem 6 and the slots 15, 16 are at right-angles to the plane formed by the axis of the guide channel 14, instead of being in this actual plane as in FIGS. 1 and 2. An inner half 17 of the housing 1 is a fixed element and an outer half 18 consists of separate segments 19, 20, 21 and 22, which are separately movable by means of forces Q, can be secured in the closed position, and can be brought by oppositely directed forces into the open position. When the housing 1 is in the open position shown in FIG. 3, the looped rod falls from between the tubes 4, 5 under its own weight and falls away from the stem 6.

In order that the tubes 4 and 5 form between them the cavity 14 for the passage of the rod when the housing 1 is open and are not able to prevent the rod from falling out, perhaps due to bearing one against the other, the tubes 5 and 4 are secured against lateral movement, as shown in respect of the inner half 17 according to FIG. 4, by a device in the form of a countersunk head rivet 23 or the like. The shank of the rivet 23 can be pressed securely into a corresponding bore 24 of the half 17.

FIG. 5 shows, by way of example, the use of the method of the invention for banding packages by means of a metal wire or strip. For this purpose, there is provided a device having the construction shown in FIG. 1, but with a housing 25 having the shape of a slotted, rectangular or square "ring" with rounded corners, but in other respects conforming with the housing of the arrangement according to FIG. 1. Thus, the housing 25 is subdivided into two halves and has slots lying in the plane of the axis of the guide channel which is represented by a chain-dotted line illustrating the bent or curved rod or wire. A package 26 to be banded is pushed centrally through the slotted ring formed by the housing 25. The package 26 is secured in the position desired for the banding operation. The housing 25 is then opened, as described in connection with FIG. 1, and the end portions 27, 28 of the banding wire projecting from end portions 29, 30 of the housing 25 are gripped mechanically and tensioned in the direction of the arrows. The wire then emerges through the inner slot of the housing 25 and already has the form of a loop or the like. By further tensioning, this loop is applied tightly around the package 26 in the manner usual with wire-banding machines, whereupon the ends of the wire are twisted and the excess portions are cut off. Another wire is inserted axially into the guide channel and can be bent or curved for another working operation with the

housing closed and be brought into position ready for another banding operation.

Instead of a sharp bend, it is also possible to provide a rounded transition, as provided in the four corners in 5 the housing 25 according to FIG. 5.

In the modification illustrated in FIG. 6, the two end portions 27, 28 of the housing 25 are bent in opposite directions from the annular plane so as to avoid bending down the end portions 29, 30 of the wire.

10 Where reference is made herein to the "thickness" of the flexible rod 13, this is always to be understood to mean the largest transverse dimension of the actual rod profile in that direction which lies parallel to the internal width of the guide channel gap or slot when the rod is introduced into the channel and through which the bent 15 or curved rod is moved out laterally from the guide.

Apparatus and mechanism capable of moving the guide components are conventional, and have been known for some time, as for instance, shown in U. S. Patent No. 20 2,136,225, to W. E. Williams, which issued November 8, 1938, in which FIG. 13A and FIG. 13B disclose a two-part guide frame in which the frame parts may be opened and closed by means of toothed racks 150, which cooperate with two gears 151. In this way, the two frame 25 parts may be moved away from each other or toward each other, in order to adjust the size of the opening for the strapping material. Also, U. S. Patent No. 2,908,215, in the name of Paul W. Fawcett, issued October 13, 1959, which shows a guide channel in accordance with FIG. 6 30 of this patent, formed by a rigid part 23 and a movable part 30. FIGS. 17 and 18 show the housing part 57, and the movable part 56, operable by means of springs 59. FIGS. 20, and 25 to 28 also show two-part guide means for use in wire-tying machines.

35 The number of flexible tubes is not restricted to three.

I claim:

1. Apparatus for bending a flexible metal wire or strip comprising at least three juxtaposed flexible tubes defining a cavity between them, a housing formed by guide 40 components holding said tubes in the shape of a desired bending path whereby said cavity forms a guide channel for said wire, at least one of said components being movable between a position in which all of said tubes are held positively at a mutual spacing less than the thickness 45 of the wire to be bent and a position in which a gap of an internal width exceeding the thickness of the said wire and extending throughout the length of said channel is formed between at least two of said tubes, said guide components forming the housing having a slot between two components through which the wire is inserted and withdrawn into and out of the apparatus.

2. Apparatus according to claim 1, in which said flexible tubes are helical springs with juxtaposed turns.

3. Apparatus according to claim 1, in which there are 55 three tubes arranged in triangular position in cross-section.

4. Apparatus according to claim 1, in which the housing has a recess therein which is T-shaped in cross-section, two of said tubes being arranged in one portion 60 of said recess and the third tube being arranged in the stem thereof, said housing being provided in two halves which are movable relatively to one another transversely of the stem so that they can be moved apart from a closed position in which they hold the three tubes mutually bearing one against the other to an open position in which said two tubes disposed in the one portion of 65 said recess have a spacing exceeding the thickness of the rod.

5. Apparatus according to claim 1, in which the housing has a recess therein which is T-shaped in cross-section, two of said tubes being arranged in one portion 70 of said recess and the third tube being arranged in the stem thereof, said housing being divided symmetrically into two halves which are adjustable relatively to one another transversely of the stem so that they can be

moved apart from a closed position in which they hold the three tubes mutually bearing one against the other to an open position in which said two tubes disposed in the one portion of said recess have a spacing exceeding the thickness of the rod, and said two tubes arranged in said one portion being secured against transverse sliding movement relatively to the half of said housing accommodating them.

6. Apparatus according to claim 1, in which at least one half of said housing is divided into segments disposed longitudinally one behind the other, and trans-

versely adjustable as such relatively to the other half of said housing.
